UNITED STATES PATENT OFFICE

2,190,410

AIR FURNACE

Clifton Mallory, Auburn, N. Y.

Application October 3, 1938, Serial No. 233,102

4 Claims. (CL 126—108)

This invention appertains to new and useful improvements in air heating plants and more particularly to an air furnace.

The principal object of the present invention is to provide an air furnace constructed in such a manner as to have a higher degree of efficiency than furnaces now generally employed in heating plants.

Another important object of the invention is to provide an air furnace for air heating systems wherein the heat can be regulated at the furnace in a desirable and convenient manner.

These and other important objects and advantages of the invention will become apparent to the reader of the following specification.

In the drawings:

Figure 1 represents a side elevational view of the furnace.

Figure 2 is a vertical sectional view.

Figure 3 is a section on line 3—3 of Figure 1.

Figure 4 is a sectional view taken substantially on line 4—4 of Figure 2.

Figure 5 is a sectional view taken substantially on line 5—5 of Figure 2.

Referring to the drawings wherein like numerals designate like parts, it can be seen that numeral 5 generally refers to the shell which consists of the side walls 6—6, the front wall 7 and the rear wall 8.

In the shell 5 are the vertically disposed internal shells 9 and 10, these shells being spaced from each other and from the end and side walls, so that air is in contact with all external surfaces thereof.

The upper opposed portions of the shells 9 and 10 are open but normally closed by the headers 11 and 12 between which extend the flue tubes 13. There is preferably a multiplicity of these tubes so that air passing upwardly in the direction of the arrows must follow a tortuous path through the spaces between the tubes.

In the lower portion of the shell 9 is the firebox 14, the grate 15 and the ashpit 16. The ashpit 16 has the door 17 while the firebox 14 has the fuel door 18. In the upper portion of the shell 9 is the heat chamber 19 and the upper portion of this has the door 20.

The top of the shell 5 is provided with the hood 21 which has a multiplicity of openings therein from which pipes extend to various parts of a house or other building.

Extending through the rear wall 8 is the flue pipe 23. Extending into the lower portion of the shell 5 at the rear wall 8 is the air inlet conduit 24 which extends to the shell 10. A drawer 26

has its outer end wall disposed directly under the side wall of the shell 10, through which the drawer is movable. The drawer has a handle 26a and is slidably on the guide or rib 27. A closure plate 26' having a handle 28 is provided for the drawer opening.

One side wall 6 is also provided with the door 28' which can be opened to permit access to the water-containing pan 29 which serves as a humidifier.

The lower portion of the side of the shell 10 opposed to the shell 9 has the opening 30 therein within which is mounted the motor-driven fan 31. This fan serves to pull air from the pipe 24 and force the same upwardly over the humidifying pan 29 and upwardly through the heat tubes 13 where the air is thoroughly heated and passes to the hood 21.

As shown in Figure 2, the upper end of the baffle plate 25 is hingedly connected as at 32 to 20 the top of the shell 10 and a hand lever 33 connects at its inner end pivotally as at 34 to the lower portion of the baffle and extends through the wall of the shell 10 and the rear wall 8 of the shell 5. This hand lever 33 has ratchet teeth 35 25 for engagement with the edge portions of the last-mentioned wall at the openings 36. Thus with the use of this hand lever 33, the baffle plate 25 can be held in any desired adjusted position for retarding or permitting free passage of the products of combustion from the heat tube 13 to the flue 23.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:

1. A heating furnace comprising an external shell, a pair of internal shells mounted within the external shell, a fire box in one of the shells, a vertically mounted baffle plate in the other shell, said baffle plate being hingedly secured at its upper end to the upper portion of the corresponding shell, a plurality of products of combustion conveying tubes extending from the fire box containing shell to the baffle plate containing shell, the lower free end portion of the baffle plate depending in the corresponding internal shell to a point below the lowermost products of combustion conveying tubes, said baffle plate containing shell having an outlet at its upper portion and at the opposite side of the baffle plate 55

from the said products of combustion conveying tubes.

2. A heating furnace comprising an external shell, a pair of internal shells mounted within the external shell, a fire box in one of the shells, a vertically mounted baffle plate in the other shell, said baffle plate being hingedly secured at its upper end to the upper portion of the corresponding shell, a plurality of products of combustion conveying tubes extending from the fire box containing shell to the baffle plate containing shell, the lower free end portion of the baffle plate depending in the corresponding internal shell to a point below the lowermost products of combustion conveying tubes, said baffle plate containing shell having an outlet at its upper portion and at the opposite side of the baffle plate from the said products of combustion conveying tubes, and a drawer slideable through an opening 10 in the outer shell and into the baffle plate containing internal shell and forming the bottom for the last-mentioned shell.

3. A heating furnace comprising an external shell, a pair of internal shells mounted within the external shell, a fire box in one of the shells, a vertically mounted baffle plate in the other shell, said baffle plate being hingedly secured at its upper end to the upper portion of the corresponding shell, a plurality of products of combustion conveying tubes extending from the fire box containing shell to the baffle plate containing shell, the lower free end portion of the baffle plate depending in the corresponding internal

shell to a point below the lowermost products of combustion conveying tubes, said baffle plate containing shell having an outlet at its upper portion and at the opposite side of the baffle plate from the said products of combustion conveying tubes, hot air outlets at the top of the outer shell, and an air inlet to the space below the products of combustion conveying tubes.

4. A heating furnace comprising an external shell, a pair of internal shells mounted within the external shell, a fire box in one of the shells, a vertically mounted baffle plate in the other shell, said baffle plate being hingedly secured at its upper end to the upper portion of the corresponding shell, a plurality of products of combustion conveying tubes extending from the fire box containing shell to the baffle plate containing shell, the lower free end portion of the baffle plate depending in the corresponding internal shell to a point below the lowermost products of combustion conveying tubes, said baffle plate containing shell having an outlet at its upper portion and at the opposite side of the baffle plate from the said products of combustion conveying tubes, an elongated member disposed through 15 openings in the outer shell and the baffle plate containing shell provided with teeth engageable with the edges of the shells through which it passes, and a pivotal connection between the elongated member and the lower portion of the 20 baffle plate.

CLIFTON MALLORY.
